UNITED STATES PATENT OFFICE.

CHARLES VACEK, OF CHICAGO, ILLINOIS.

NECKTIE HOLDER.

Application filed June 13, 1921. Serial No. 477,171.

To all whom it may concern:

Be it known that I, CHARLES VACEK, a citizen of Czechoslovakia, residing at Chicago, in the county of Cook and State of Illinois, have invented certain new and useful Improvements in Necktie Holders; and I do hereby declare the following to be a full, clear, and exact description of the invention, such as will enable others skilled in the art to which it appertains to make and use the same.

This invention relates to necktie supporting means for holding the tie in position without the necessity of passing the same around a collar and obviating the practice of forming the tie into a knot each time the same is worn or fitted to the collar.

The invention is designed for use in connection with a tie of the four-in-hand type, the device constituting a holder and a form for the tie, which is mounted thereon.

Other objects and advantages will be apparent and suggest themselves as the nature of the invention is understood.

While the drawings illustrate an embodiment of the invention, it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a front view of the holder, and

Figure 2 is an edge view thereof.

Corresponding and like parts are referred to in the following description and designated in the several views of the drawings by like reference characters.

The holder may be constructed of any suitable sheet material and in general appearance is of Y-form and comprises a stem 1 and oppositely disposed arms 2 at one end of the stem. The arms 2 are rear-

wardly and oppositely inclined and are joined to the stem 1 in a manner to provide a depression 3 in line with the stem. The outer edges of the arms 2 merge into the outer edges of the stem 1, whereas the upper edges of the arms are abruptly deflected at their inner ends to provide the depression 3. As a result the inner ends of the arms 2 are constricted at their junction with the stem and this is of advantage in the formation of the tie as it prevents the same from slipping or becoming displaced. The lower end of the stem 1 is expanded, as indicated at 4, to prevent vertical displacement of the holder after the tie has been formed thereon. A clip 5 of any approved construction is applied to the rear side of the expanded end 4 and serves as means for attaching the holder to the front of the shirt when the device is in position. The arms 2 pass between the folds at the ends of a turn-down collar and act jointly with the clip 5 to retain the holder with the attached tie in proper and appropriate position.

What is claimed is:

A necktie holder comprising a body, a pair of bowed rearwardly and oppositely inclined arms carried by said body at its upper end, said arms being reduced where they join the body to provide a depression between the adjacent ends of the arms to prevent displacement of the tie, the lower end of the body being expanded, a clip carried by said expanded portion at the rear side thereof, the arms serving to hold the device in place on a collar, and the expanded portion cooperating with the depression to hold a tie in place on the device.

In testimony whereof I affix my signature in presence of two witnesses.

CHARLES VACEK.

Witnesses:
